SAFETY SHIELD FOR ELECTRIC OUTLETS

Harry W. Hooser, Las Vegas, Nev.

Application May 28, 1949, Serial No. 95,930

5 Claims. (Cl. 174—67)

1

This invention relates to a safety shield for electric outlets, and more particularly to a shield for the customary electric outlets ordinarily placed in walls, baseboards and the like, and having one or more sockets for plugging in any desired electrical fixture.

An object of my invention is to provide a cover or shield for electric outlets so as to protect small children from exploring the possibilities thereof with small fingers, bits of wire, and the like, with the attending danger of burns or deadly shock.

Another object of my invention is to provide a safety shield for electric outlets which is so simple in design as not to suggest an attractive nuisance and it will therefore be overlooked by children.

Another object of my invention is to provide a cover or safety shield for electric outlets which is effective in preventing dust and other foreign matter from getting into the outlets.

Another object of my invention is to provide a safety shield for electric outlets which requires the simultaneous application of pressure and a lifting motion for operation so that it will be difficult for even large children to manipulate it, and yet adults can use it with ease.

Another object of my invention is to provide a safety shield for electric outlets which is inexpensive to manufacture, attractive in appearance, efficient in use and durable in construction.

Other and further objects and advantages of my invention will appear from the following description taken in connection with the accompanying drawing in which like characters of reference designate corresponding parts throughout the several views, and wherein:

Fig. 1 is a plan view of the body of my shield with cover removed.

Fig. 2 is a side view of the device shown in Fig. 1.

Fig. 3 is a bottom end view of the device shown in Fig. 1.

Fig. 4 is a plan view of the cover for my shield.

Fig. 5 is a side view of the device shown in Fig. 4.

Fig. 6 is a bottom end view of the device shown if Fig. 4.

Fig. 7 is a plan view of a complete safety shield for electric outlets embodying my invention.

Fig. 8 is a top view of the device shown in Fig. 7.

Fig. 9 is a cross-sectional view taken along the line 9—9 in Fig. 1.

Fig. 10 is a cross-sectional view taken along the line 10—10 in Fig. 7.

In the embodiment chosen for illustration, a 55

2

base plate 11 is provided on the face thereof with a pair of raised slide bars 12, 12' spaced from the sides of said plate, as shown in Fig. 3, the slide bar 12 being spaced farther from the side of the plate 11 than is the slide bar 12' and being provided with a plurality of fastening means or notches 13, 13', 13'' cut in its outer edge for a purpose to be more fully described hereinafter. The base plate 11 is also provided with upstanding sides 14, 14' having turned flanges 15, 15', respectively, which overhang the channels provided between the upstanding sides 14, 14' and the slide bars 12, 12'.

The base plate 11 is designed to fit over the ordinary electric outlet box and may replace the cover customarily provided. The base plate is apertured, as at 16, 16' to receive and permit access to the ordinary electric sockets, and is provided with a hole 17 through which a screw (not shown) is inserted for fastening the device in place.

The sides 14, 14' extend outwardly beyond the slide bars 12, 12' sufficiently so that a cover 18 is slidably received between the flanges 15, 15' and the slide bars 12, 12'. The cover 18 is provided with longitudinally extending guide bars 19, 19' along opposite sides of its back. The guide bars 19, 19' fit into and slide within the channels defined by the slide bars 12, 12', respectively, the guide bar 19 being provided near the bottom of the cover 18 with a latch or projection 20 for co-operation with the notches 13, 13', 13'' in the slide bar 12, as will be more fully described hereinafter.

The lower portion of the cover 18 is curved or bowed outwardly, as at 21; and when the cover is resting in place on the base plate 11, the projection 20 is received within the notch 13, as clearly shown in Fig. 7, and holds the cover securely in place; however, if pressure is applied upon the resilient bowed portion 21, the resilient bowed portion will yield and flex so that projection 20 will be removed from engagement with the notch 13 and the cover 18 can then be pulled upwardly. A tab 22 is provided on the upper end of the cover 18 to assist in raising and lowering the cover. A bottom bar 23 extending across the lower end of the base plate limits the downward movement of the cover 18, and closes the bottom of the channels within which the guide bars 19, 19' slide.

In practice, when my shield is placed over an electric outlet and screwed into place, the cover 18 can only be removed by applying pressure on the bowed section 21 to release the projection 20 from the notch 13 and simultaneously pulling

upwardly on the cover or tab 22. When this simultaneous pressing and pulling force is applied, the cover 18 can be slid upwardly. As the cover progresses upward it will uncover the socket beneath the opening 16, and if pressure is released from the bowed section 21, the projection 20 will catch in the notch 13' and hold the cover securely in that position. If it is desired to uncover the socket beneath the opening 16', pressure can again be applied to the bowed section 21 and by simultaneously pulling upon the tab 22 the cover can be slid upwardly until the projection 20 engages the notch 13'', or the cover 18 can be removed entirely, as will be understood, by a farther simultaneous pressing and pulling action as described above. To lower the cover 18 to close it so as to prevent inadvertent access to the electrical outlet, it is merely necessary to push downward on the tab 22, whereupon the cover slides easily down against the bottom bar 23.

My shield is adaptable for construction from materials customarily used in the construction of covers for electric outlets and may be made from plastic, either clear or colored. It will be apparent from the construction of my shield that while it is neat and attractive in appearance it will not entice children to pry into it, and the double action required to open it is simple for adults, not generally susceptible of comprehension by children and is therefore substantially fool proof.

It will be obvious to those skilled in the art that many modifications and changes can be made in the embodiment shown without departing from the scope of my invention as defined in the appended claims.

I claim:

1. A safety shield for electric outlets comprising a base apertured to receive electric outlet sockets, a cover slidably mounted on said base and covering apertures for electric sockets in said base, a plurality of fastening means on said base, latch means on said cover engaging one of said fastening means and holding said cover against displacement, said cover having a bowed resilient portion and being arranged to flex to disengage said latch means from said one of said fastening means when pressure is applied to said bowed portion, whereby said cover can be moved upwardly to selectively expose said apertures for electric sockets in said base.

2. A safety shield for electric outlets comprising a base apertured to receive an electric outlet socket, a cover slidably connected to said base and covering said aperture for an electric socket in said base, fastening means on said base, latch means on said cover engaging said fastening means and holding said cover against displacement, said cover having an outwardly bowed resilient portion and being arranged to flex to disengage said latch means from said fastening means when pressure is applied to said bowed portion, whereby said cover can be moved upwardly to expose said aperture for an electric socket in said base.

3. A safety shield for electric outlets comprising a base having slide bars spaced from the sides thereof, one of said slide bars having a notch in its outer edge, upstanding sides on said base cooperating with said slide bars to form channels,

flanges on said sides overhanging said channels, said base plate being apertured to receive an electric outlet socket, a cover slidably received between said flanges and said slide bars and covering said aperture for an electric socket in said base, guide means on said cover slidably positioned within said channels, means on one of said guide means received within said notch and holding said cover against lateral displacement, said cover having an outwardly bowed resilient portion adjacent said projection and being arranged to flex to disengage said projection from said notch when pressure is applied to said bowed portion, whereby said cover can be moved upwardly to expose said aperture for an electric socket in said base.

4. A safety shield for electric outlets comprising a base having a pair of slide bars spaced from the sides thereof, one of said slide bars having a notch in its outer edge, upstanding sides on said base cooperating with said slide bars to form channels, flanges on said sides overhanging said channels, said base being apertured to receive an electric outlet socket, a cover slidably received between said flanges and said slide bars and covering said aperture for an electric socket in said base plate, guide bars on said cover slidably positioned within said channels, a projection on one of said guide bars received within said notch and holding said cover against lateral displacement, said cover having an outwardly bowed resilient portion adjacent said projection and being arranged to flex to disengage said projection from said notch when pressure is applied to said bowed portion, whereby said cover can be moved upwardly to expose said aperture for an electric socket in said base.

5. A safety shield for electric outlets comprising a base plate having a pair of slide bars spaced from the sides thereof, one of said slide bars having a plurality of notches in its outer edge, upstanding sides on said base plate cooperating with said slide bars to form channels, inturned flanges on said sides overhanging said channels, said base plate being apertured to receive electric outlet sockets, a cover slidably received between said flanges and said slide bars and covering apertures for electric sockets in said base plate, guide bars on said cover slidably positioned within said channels, a projection on one of said guide bars received within one of said notches and holding said cover against lateral displacement, said cover having an outwardly bowed resilient portion adjacent said projection and being arranged to flex to disengage said projection from said notch when pressure is applied to said bowed portion, whereby said cover can be moved upwardly to selectively expose said apertures for electric sockets in said base plate.
